Atty's

UNITED STATES PATENT OFFICE

WILLIAM E. URSCHEL, OF VALPARAISO, INDIANA

BUILDING FORM

Application filed December 14, 1927. Serial No. 232,901.

My invention relates in general to a building form and has more particular reference to an improvement in building forms of the type described in my prior United States Patent, Number 1,636,396.

The type of building form to which this invention applies is that used in connection with the construction of monolithic walls, and the like, which are formed of concrete or similar material which is arranged to form a wall when in plastic condition and then allowed to harden or set, building forms being used to support the material in position till the material hardens, and forms a self-supporting wall. Such walls are usually built in courses, that is to say, the wall is built up to a convenient height, which is limited by the size of the forms, and as soon as the material has set sufficiently, the forms are removed and arranged at the top of the wall to support the wall material of the new course till it hardens. The forms are then removed and again arranged at the top of the wall to accommodate the succeeding course.

It will be readily appreciated that, to construct a wall, vertical throughout its entire height, the forms must be carefully adjusted as each course is formed. Such adjustment requires time and care, increases building costs, and has heretofore been regarded as unavoidable. It is my desire to provide a self-aligning form, the use of which will eliminate the necessity of using extreme care and accuracy during adjustment of the form, the form being automatically self-adjusting.

The principal object of my invention is the provision of an improved building form having self-aligning features.

Another important object of the invention is the reduction of building costs by means of my improved self-aligning building form.

Still another important object of the invention is the provision, in a building form, having a tie rod for securing the sides of the form in spaced relationship and supporting the same in position on a wall to receive building material, of a form clamp

adapted to align the sides of the form and also to form a groove across the top of the building material while supported by the form, which groove is shaped to engage and adapted to support the tie rod and to maintain the same and the building form in proper alignment on the wall.

Numerous other objects and advantages of the invention will be apparent as it is better understood from the following description, which, taken in connection with the accompanying drawings, discloses a preferred embodiment of the invention.

Referring to the drawings:

Figure 1 is a perspective view of a wall during construction showing building forms of my invention in position thereon;

Figure 2 is a perspective view similar to that of Figure 1, the building forms having been removed after the setting of the course;

Figure 3 is a vertical cross section taken substantially along the line 3—3 in Figure 4; and

Figure 4 is a vertical cross section taken substantially along line 4—4 of Figure 1.

To illustrate my invention, I have shown on the drawings the upper portions of a wall 11, under construction by the so-called "course" method. A freshly poured course 13 is shown at the top of the wall 11, supported between building forms. These forms comprise a series of co-operating sections 15 which are secured in position on opposite sides of the completed wall 11, and extend upwardly therefrom in parallel relationship, being secured in position on the wall by means of tie rods 17, the ends of which pass through registering apertures 33 formed in the sides of co-operating sections 15, near the lower edges thereof. Each tie rod rests in a groove 63 formed across the top of the wall. The groove 63 is formed, as will be hereinafter more fully explained, in such a manner that it has a definite angular relationship with the vertical wall surface. In the preferred embodiment shown, the groove is perpendicular to the wall surface.

Each form section 15 comprises a substantially rectangular face plate 21, having

angle irons 23 of substantially T-shaped cross section arranged along the upper and lower edges of the face plate 21 for the purpose of strengthening the same. The top portion 24 of the T engages the surface of the face plate and the shank or body 26 forms a flange extending outwardly from the face plate. Both the upper and lower angle irons of each section 15 extend laterally beyond a side edge of the face plate 21 to engage the face plate of the adjacent section, the abutting end of the angle iron 23 of the adjacent section being cut away at 30 to receive the said extended end of 10 the angle iron. The body 26 of the angle irons also are extended in both directions beyond the edges of the face plate and one said extended end 31 is offset as at 25 to overlap the opposite extended end 32 of 15 the flange of the adjacent section. These extended portions are apertured to receive pins 27 which secure the flanges of adjacent form sections together. Angle irons 28 of substantially L-shaped cross section are secured along the end edges of the face plate 21, and intermediate angle irons 29 of U-shaped cross section are arranged across the face plate between the top and bottom angle irons 23 for the purpose of strengthening 20 the form section. The angle irons 23, 28 and 29 may be secured to the face plate and to each other in any convenient manner, such as by spot welding, or the like, or by rivets. The tie rod apertures 33 are formed 25 in the section through the lower ends of the U-shaped angle irons 29, the top 24 of the lower angle iron 23, and the face plate, and accommodate the tie rods which extend between the co-operating form sections to 30 secure the same upon the wall. The tie rods are provided with a plurality of spaced diametral holes 35 extending from one end to adjacent the mid portions of the rod, and the opposite end of the rod 15 is threaded 35 for engagement with a nut 37. The diametral holes 25 are formed to receive a pin 36 adapted to engage one section. The rod thence extends across the wall and through the co-operating section, which is secured to 40 the tie rod by means of the nut 37. The tie rods lie in the grooves 63, which, being formed at right angles to the wall surfaces, allow the rods to support the form sections in definite relationship on the wall. 45 The upper portions of co-operating form sections are maintained in spaced relationship by means of the form clamp 19 which comprises a bar 39 having an integral arm 41 arranged at one end. The bar 39 is 50 adapted to carry a slide 45 having an integral arm 43 similar to the arm 41. The bar 39 is provided with a series of spaced holes having a spacing similar to that of the diametral holes 35 in the tie rod, and 55 the slide 45 is provided with apertures 49

adapted to receive a bolt and nut 51 in position to engage a desired one of the spaced holes 47 in order to secure the slide 45 in a desired position on the bar 39, according to the width of the wall being built. The 70 bar 39 is provided with a notch 53 adjacent the arm 41 and the slide 45 is provided with a similar notch adjacent the arm 43. These notches are adapted to receive the upper edges of the co-operating form sections which are thus maintained in spaced relationship, determined by the position of the slide 45 on the bar 39. The notches 53 define pivot points at which the upper edges of the form sections may be pivotally 75 mounted. It will be apparent that these notches embrace the upper edges of the form sections when the clamping bar assembly is arranged in position thereon. Inasmuch as the form sections may rock with 80 respect to the wall to which they are mounted, the upper edges of the form sections must necessarily be pivotally seated in the grooves. The ends of the arms 39 and 41, when in position embrace the upper portions 85 of the co-operating form sections and each is provided with a threaded journal 55 in which the shank of a thumb screw 57 engages. The end of the thumb screw bears 90 upon a casting 59 which forms a seat for receiving the end of the shank. This casting is secured to the form section within a U-shaped angle iron 29 and vertically above the tie rod aperture 33. By adjusting the thumb screw 57, the form sections may be 95 quickly adjusted to vertical position, the upper edges of the co-operating sections being held in spaced relationship in the notches 53 and the thumb screws providing a means for rotating the form sections in the 100 notches until vertical position is reached. 105 The bar 39 is provided with a lower edge 61, having a rounded formation, disposable between the form sections in such a manner that when the space between the sections is completely filled with building material, the lower surface of the bar will rest in the upper surface of the building material and, since the latter is poured between the forms in a plastic condition, will cause a transverse groove to be impressed across the top of the wall. The rounded surface 61 of the bar is such that the groove 63 formed by the bar has a shape corresponding with the contour of the tie rod 17, that is to say, is adapted to receive the tie rod when the forms are replaced for 110 the purpose of supporting the succeeding course. Since the groove 63 is formed in the top of the course by the clamp bar 39 after the latter has been arranged in final 115 adjusted position, it will have a definite relation to the position of the form and consequently to the surfaces of the wall. The parts are arranged so that the bar 39 120 125 130

is vertically above and parallel to the tie rod 17 when the forms are in arranged position, and consequently, when the tie rod is arranged in the groove, the forms will automatically assume a proper relation to the top of the wall. The forms are thus adapted to align themselves upon the wall when they are placed in position to receive the building material, the only necessary adjustment being manipulation of the thumb screws 57 to bring the forms into plumb. I have shown, on the drawings, form sections having two tie rods per section, but it will be understood that any convenient number of rods may be used.

The forms may be removed from the wall after the course is set by first removing the clamps 19, and then withdrawing the tie rods 17 from the grooves in which they were arranged when the forms were first positioned upon the wall. The tie rod leaves a cylindrical hole 65 through the wall, which may be filled with wooden plugs to which furring strips may be conveniently attached, or the holes may be plugged with fresh building material after the wall has been completed.

Having thus described my invention, what I claim as new and desire to secure by Letters Patent is:

1. In a building form comprising side plates, a tie rod for securing the lower portions of the side plates upon a wall, and a clamp for maintaining the upper portions of the side plates in spaced relationship, means formed on the said clamp for forming a groove in the material contained within the form and additional means carried by said clamp for adjusting the angular position of the walls of the form with respect to the wall.

2. In a building form comprising side plates, a tie rod for securing the lower portions of the side plates upon a wall and a clamp for maintaining spaced relation of the upper portions of the side plates, means formed on the said clamp for forming a groove in the material contained within the form, said groove being adapted to receive the tie rod and align the form in position on the wall when positioned for the succeeding course and additional means carried by said clamp for adjusting the angular position of the walls of the form with respect to the wall.

3. In a building form comprising side plates and a tie rod for the bottom of said side plates, a clamp having projecting arms and notches adjacent said arms defining pivot points for said side plates, said arms adjustably engaging said side plates for aligning the same, said clamp having a portion arranged for forming a groove in the material contained within the form, said groove being adapted to receive the tie rod

and align the form on the wall when positioned for the succeeding course.

4. In a building form comprising side plates adapted to support a wall course and a tie rod for supporting the side plates on a wall, a clamp having arms embracing the upper portions of said plates, notches adapted to engage the edges of said plates adjacent said arms to provide pivot points for said plates and means carried by said arms for adjusting the position of the plates in the pivot points, said clamp having a portion adapted to form a transverse groove in the top of the wall course, said groove being parallel to the tie rod.

5. In a building form, side plates adapted to support a wall course, a tie rod for maintaining the lower portions of said wall portions in spaced relationship and a clamp having arms embracing the upper portions of said wall portions, and having notches adapted to receive the edges of said wall portions and to provide pivot points for the wall portions and means carried by said arms for adjusting the relative position of the walls in the pivot points.

6. In a building form, side plates adapted to support a wall course, a tie rod for maintaining the lower portions of the plates upon a wall, an adjusting clamp for said plates having arms embracing the sides thereof, said clamp being provided with notches adapted to receive the upper edges of said plates and said arms being provided with threaded means for adjusting the angularity of the plates in the notches whereby the building form may be aligned upon a wall.

7. In a building form, side plates, a tie rod for securing the lower portion of the side plates in spaced apart relationship, spacing means for maintaining the upper parts of the side plates in spaced relationship and adjustable means carried by the spacing means to clamp the plates in a desired angular relationship on the wall, the spacing means being arranged to form a groove in the material arranged in the form vertically above and parallel to said tie rod.

8. In a building form, side plates adapted to support a wall course, a tie rod for maintaining the lower portion of the plates in spaced relationship and an adjustable clamp for maintaining the upper portions of said plates in spaced relationship, said clamp having an arm embracing the sides of a plate, said clamp being provided with means to receive the upper edges of said plates and the arm being provided with adjustable means for clamping the parts in place, said clamp being positioned vertically above said tie rod in position to form a groove in the material in the form above and parallel to said tie rod.

9. In a building form, side plates, a tie rod for securing the lower portion of the

- side plates in spaced apart relationship, spacing means for maintaining the upper parts of the side plates in spaced relationship and adjustable means carried by the 5 spacing means to clamp the plates in a desired angular relationship on the wall, said spacing means being arranged to form a groove in the material arranged in the form above and parallel to said tie rod.
- 10 10. In a building form, side plates, a tie rod for securing the lower portions of the side plates in spaced apart relationship, spacing means for maintaining the upper portions of said plates in spaced relationship and an adjustable, manually operable, threaded clamp means carried by the spacing means for securing the plates in a desired angular position, said spacing means being arranged to form a groove in the material arranged in the form above and parallel to said tie rod.

In witness whereof, I have hereunto subscribed my name.

WILLIAM E. URSCHEL.
